VALVE SPRING LIFTING MECHANISM

Filed Nov. 15, 1922

2 Sheets-Sheet 2

UNITED STATES PATENT OFFICE.

LOUIS M. WOOD, OF NEW YORK, N. Y., ASSIGNOR TO SPEED-O MULTIPLE VALVE LIFTER CORPORATION, OF NEW YORK, N. Y., A CORPORATION OF NEW YORK.

VALVE-SPRING-LIFTING MECHANISM.

Application filed November 15, 1922. Serial No. 601,000.

To all whom it may concern:

Be it known that I, LOUIS M. WOOD, a citizen of the United States, residing at New York city, in the county of New York 5 and State of New York, have invented certain new and useful Improvements in Valve-Spring-Lifting Mechanism, of which the following is a specification.

This invention relates to valve spring lifting mechanism for internal combustion engines, an object of the invention being to provide an improved mechanism for elevating and maintaining under compression a plurality of valve springs, which mechanism will be relatively simple in construction, relatively inexpensive to manufacture, 10 easy to operate, and efficient and effective for the purposes for which it is designed.

A further object of this invention is to provide mechanism for elevating under compression the valve springs of the engine, the mechanism having improved means for compressing the valve springs by cam action, thereby minimizing the power necessary to 15 operate the mechanism.

A further object of this invention is to provide an improved lifting bar for valve spring lifting mechanism, the bar being guided with relation to the springs in an improved manner.

A further object of this invention is to provide lifting mechanism for valve springs having improved means for maintaining the mechanism in elevated position with the 20 valve springs held under compression.

A further object of this invention is to provide an improved valve spring lifting lever having one or more cam surfaces adapted to coact with a lifting member for 25 facilitating the operation thereof.

Other objects of this invention will appear in the following description thereof, reference being had to the accompanying drawings forming a part of this specification, 30 wherein like reference characters indicate corresponding parts in the several views and wherein Fig. 1 is a front view in elevation illustrating an embodiment of my improved mechanism adapted for use with a four cylinder engine; Fig. 2 is a sectional elevation

taken substantially on lines 2—2 of Fig. 1; Fig. 3 is a fragmentary sectional elevation illustrating the mechanism in elevated position; Fig. 4 is a perspective view of the lifting member; Fig. 5 is a fragmentary end view of the lifting member in elevated position; Fig. 6 is a fragmentary detail view of a form of lifting lever; Fig. 7 is a detail view partly in section of a modified form of lifting member; and Fig. 8 is a detail sectional view taken through one end of the lifting member.

In the drawings I have illustrated a present preferred form of my invention as used in connection with a four cylinder engine. 35 The motor block of the engine is provided with the usual valve spring chamber 9 adapted to be closed at the front thereof with a cover plate (not shown), the cover plate being held in position by a suitable stud or bolt 50 and nut 51. The valve spring chamber 9 is located within a housing or casing comprising a rear wall 10 and forwardly extending end walls 11, the latter adapted to form guide means for the valve 40 spring lifter bar as hereinafter described. The front of the valve spring housing is also provided with the usual depending lip or flange 12 extending along the top edge thereof and an upwardly projecting lip or 45 flange 13 extending along the lower edge thereof. The cover plate is bolted against the outer faces of the flanges 12 and 13, and as hereinafter shown the lower flange or lip 13 is utilized as a means for fulcruming the 50 lifting lever. The valves 14 are provided with valve stems 15 which extend into the chamber 9, and adjacent to the lower ends 55 of the valve stems are located retaining pins 16 against which the valve spring retaining seats 17 impinge when in normal position, the seats 17 being constructed to receive the ends of the valve springs 18 which are held 60 between the upper wall of the chamber 9 and the seats 17. The lower wall of the 65 chamber 9 is provided with the usual guide members 19 through which the valve lifters 70 extend, the latter being operated by suitable cams on the cam shaft of the engine.

The lifting member for the present mecha- 75

nism comprises a bar 21 terminating at opposite ends thereof in guide portions 22. When the bar is applied to the front of the housing the guides 22 overlie the ends 11 of the housing and are guided thereby in a vertical plane. Extending from the bar or member 21 is a valve spring operating portion 23, preferably as in the present instance, cast integrally with the upright bar 21 and forming a part thereof. At suitable intervals the member 23 is provided with recesses 24 adapted to freely embrace the valve stems 15 and permit the seating of the retainers 17 on the upper surfaces of the member 23. The latter is also provided with recesses 25 for permitting the lifting bar to clear the guide sleeves 19.

Intermediate the ends of the bar 21, the latter is preferably enlarged at 26 and a vertical guide slot 27 is formed therein. The rear of the lifting bar 21 is also enlarged and reinforced at 28 through which extends a vertical guide slot 29 registering with the guide slot 27 and a horizontal guide slot 30 also registering therewith. Adjacent to the opposite ends of the lifting bar a pair of slots 31 are provided, and within each slot is pivoted at 34 a locking or supporting member or leg 35 having at the lower end thereof a notch or detent 35^a. It will be noted that the upper edge 36 of each locking member 35 extends at a predetermined angle so that when the member or supporting leg 35 is swung outwardly as shown in Fig. 8, the inclined edge 32 of the slot 31 will form a stop against which the edge 36 impinges. The lower inclined edge 33 of the slot 31 also forms a stop for limiting the rearward swinging of the member 35.

The supporting latches or legs 35 are automatically swung into various positions by means of springs 37 pivoted to the bar 21 as by means of screws 38. The springs 37 may be provided at the free ends thereof with suitable thumb pieces 39 engaging notched or recessed edges 39^a formed in the members 35, so that upon swinging the springs 37 so that the thumb pieces 39 will engage the upper part of the recesses 39^a the members 35 will be swung outwardly by the action of the springs, and upon shifting the springs so that the thumb pieces will be located at the lower part of the recesses 39^a, the members 35 will be swung inwardly by the action of the springs. Thus the springs will swing the members 35 either outwardly or inwardly depending upon whether the ends 39 engage the members 35 above or below the pivots 34.

The lifting bar 21 is operated by means of a lever 40, which in the present instance is provided with fork or bifurcated ends 41 having the upper edges 42 thereof curved or inclined to form cam surfaces. The ex-

tremity of each fork or member 41 is notched at 43 so as to coact with the projecting lip or flange 13 of the housing when the lever is placed in position as illustrated particularly in Figs. 2 and 3. It will be noted that the front edge 43' of the bar 21 is rounded or curved so as to form a cam surface adapted to coact with the inclined or curved cam surfaces 42 of the lifting lever 40.

As illustrated in Fig. 7 the bar 21 may be provided with a spring retainer engaging portion 44 suitably recessed at 46 so as to freely embrace the valve stems 15. These recesses are countersunk to provide counter-recesses terminating in valve spring retainer seats 45, which are preferably curved or shaped so as to correspond to the shape of the spring retainers 17 and into which the retainers are seated. The seats 45, it will therefore be seen, form guides for receiving and centering the retainers 17, and therefore assist in guiding the lifting bar 21 with relation to the valve springs 18.

In the operation of the present improved lifting mechanism the nut 51 on the outer end of the stud or bolt 50 is removed for the purpose of removing the cover plate and lifting bar 21 placed in position with the bolt 50 extending through the guide slots 27 and 29. The nut 51 is then screwed onto the end of the bolt 50, the portions 23 or 44 of the lifting bar 21 extending under the valve spring retainer seats 17 and against which the latter are seated. The thumb pieces 39 of the springs 37 are then shifted to the lower portions of the guide recesses 39^a and the lever 40 placed in position as illustrated in Fig. 2. Upon swinging the handle of lever 40 upwardly, the curved or inclined cam surfaces 42 will engage the rounded cam surface 43' at the under side of the bar 21, thereby lifting or elevating the bar 21 and lifting the springs 18 simultaneously under compression. During this operation the cam surfaces 42 will be shifted over and relatively to the cam surface 43' and the construction of these surfaces reduces considerably the amount of power necessary to lift and compress the valve springs.

Also during this operation the springs 37 urge the locking members 35 against the lip or flange 13, and when the notches 35^a register with the upper edge of the lip 13 the springs will swing the members 35 inwardly to the position illustrated in Figs. 3 and 5, the members 35 thus locking and supporting the bar 21 in elevated position. The lever 40 may then be removed and the operator may readily remove the retaining pins 16 and the valves 14. After the grinding operation the valves are reinserted and the pins 16 replaced. Thereupon the lever 40 is again placed in position and the thumb pieces 39 of springs 37 shifted to the upper ends of the guide recesses 39^a, so that

upon lifting the bar 21 slightly by means of the lever 40 the springs 37 will swing the locking members 35 outwardly with the notches 35^a free of the lip or flange 13. The 5 expansion of the valve springs will then lower the bar 21 and reseat the valve spring seats 17 on the retaining pins 16.

It will be noted that the guide portions 10 22, at the ends of the lifting bar 21, engage the housing in front of the valve springs and are guided thereby in a vertical plane, thus preventing the lifting bar from shifting inwardly during the operation of the lifting lever. Furthermore the guide slots 27, 29, 15 and 30 embrace the bolt or stud 50, and without exerting any substantial pressure thereagainst enable the lifting bar to be centered with relation to the retaining seats 17 and also guide the lifting bar against endwise 20 movement during operation. Furthermore the seats 45, as shown in Fig. 7, are adapted to form guides for receiving the valve spring seats 17 and for permitting the lifting bar 21 to be guided with relation to the springs 25 18, and valve stems 15.

It will be understood that by describing in detail herein any particular form, structure or arrangement it is not intended to limit the invention beyond the terms of the 30 several claims or the requirements of the prior art.

I claim as my invention:

1. In a valve spring lifter, the combination of a lifting bar having means for operating 35 against a plurality of valve springs, and an operating member supported for operation by the engine beneath said lifting bar, said bar having a curved cam portion and said member having a cam shiftable into engagement with said cam portion for elevating said lifting bar.

2. In a valve spring lifter, the combination of a lifting member adapted to extend beneath a plurality of valve springs, and means 45 supported for operation by the engine beneath said lifting member for elevating said member and comprising a detachable operating member, said lifting member and means having coacting curved cam surfaces.

3. In a valve spring lifter, the combination of a lifting member, means for operating said lifting member against the valve springs and comprising a plurality of cams operating against said lifting member, and an operating handle for said cams.

4. In a valve spring lifter, the combination of a lifting member having means operative beneath the valve springs for lifting the same, means for operating said member and comprising a pair of spaced cams having lifting engagement with said member, and a single operating means for controlling said cams.

5. In a valve spring lifting mechanism, the 65 combination of a lifting member comprising

a vertical portion and a horizontal portion operable against the valve springs, said member having a curved cam surface, and means supported for operation by the engine and engaging said cam surface for lifting the 70 member.

6. Valve spring lifting mechanism comprising an angle bar having horizontal and vertical portions, said vertical portion having a guide portion projecting longitudinally 75 beyond the end of said vertical portion and also below the same.

7. In a valve spring lifter the combination of a lifting bar having means for operating against a plurality of valve springs, and means supported for operation by the engine beneath said lifting bar for elevating the same, said means comprising a curved cam fulcrumed independently of said bar and shiftable transversely thereof for elevat- 85 ing the same.

8. A lifting bar for valve spring mechanism having a plurality of guide portions of greater width than the bar, one of said portions having a vertical guide slot and one 90 thereof having shiftable locking means extending thereto.

9. A lifting bar for valve spring lifting mechanism having a pair of transversely extending guide slots for receiving a housing 95 bolt of the engine.

10. A lifting bar for valve spring lifting mechanism having intermediate the ends thereof an enlarged portion provided with transverse guide slots adapted to receive the 100 housing bolt of an engine.

11. In a lifting member for valve spring lifting mechanism, an angle bar comprising a vertically disposed portion having a vertical 105 guide slot for embracing a stud or bolt.

12. A lifting member for valve spring lifting mechanism comprising an angle bar formed from a pair of transversely extending members, one thereof having recesses for embracing a plurality of valve stems, said 110 members having communicating guide slots.

13. In a valve spring lifter the combination of a lifting bar having means for operating against a plurality of valve springs, means for elevating said bar, swinging locking means for maintaining the bar in elevated position, and means for limiting the swinging movement thereof.

14. In a valve spring lifter, the combination of a lifting member operative against a plurality of valve springs, means for lifting the same, a shiftable locking support for said member, and resilient means shiftably engaging said support for shifting the same.

15. In a valve spring lifting mechanism, a lifting member, a swinging support pivoted thereto, and means adapted to engage said support at opposite sides of the pivot for swinging the same.

16. In a valve spring lifting mechanism,

the combination of a lifting member comprising a vertical portion and a horizontal portion extending beneath a plurality of valve springs, an operating member supported for operation by the engine, and a cam controlled by said operating member and shiftable into position for elevating said lifting member.

17. In a valve spring lifter the combination of an angle bar comprising a vertical

portion and a horizontal portion, one thereof having a curved cam portion, and cam means supported for operation by the engine for operating said angle bar and comprising a detachable operating member and a cam controlled thereby and engageable with said curved cam portion. 15

Signed at New York city, N. Y., this 4th day of November, 1922.

LOUIS M. WOOD.
